UNITED STATES PATENT OFFICE.

THEODORE G. LEWIS, OF BUFFALO, NEW YORK, ASSIGNOR TO BUFFALO DENTAL MANUFACTURING COMPANY, OF BUFFALO, NEW YORK, A CORPORATION OF NEW YORK.

DESIGN FOR A DENTAL COTTON-HOLDER.

56,181.

Specification for Design.

Patented Aug. 24, 1920.

Application filed December 10, 1919. Serial No. 343,928. Term of patent 7 years.

To all whom it may concern:

Be it known that I, THEODORE G. LEWIS, a citizen of the United States, residing at Buffalo, in the county of Erie and State of New York, have invented a new, original, and ornamental Design for Dental Cotton-Holders, of which the following is a specification, reference being had to the accompanying drawings, forming part thereof, in which—

I claim:

The ornamental design for a dental cotton holder, as shown.

THEODORE G. LEWIS.
